UNITED STATES PATENT OFFICE.

IRVING HODGSON LONG AND SAMUEL AUGUSTUS MILLIGAN, OF LOUISVILLE, KENTUCKY;
DENNIS H. LONG ADMINISTRATOR OF SAID IRVING HODGSON LONG, DECEASED.

CORE-ARBOR.

No. 918,564.

Specification of Letters Patent.

Patented April 20, 1909.

Application filed February 1, 1908. Serial No. 413,797.

To all whom it may concern:

Be it known that we, IRVING HODGSON LONG and SAMUEL AUGUSTUS MILLIGAN, both citizens of the United States, and residents of Louisville, in the county of Jefferson and State of Kentucky, have invented a new and Improved Core-Arbor, of which the following is a full, clear, and exact description.

The invention relates to the manufacture of cast iron pipes having integral branches, and its object is to provide a new and improved core arbor for use in green sand or sharp sand cores, and arranged to permit of readily and securely interlocking the branch core arbor with the main core arbor, without danger of the branch core sagging or becoming loose, and to allow convenient and quick unlocking of the branch core arbor and removing the cores from the pipe after the casting operation is completed.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a plan view of the improvement, arranged as a core arbor for casting a pipe having a single branch; Fig. 2 is an enlarged sectional plan view of the coupling for interlocking the branch core arbor with the main core arbor; Fig. 3 is an enlarged face view of the main core arbor having the socket; Fig. 4 is a perspective view of part of a branch core arbor provided with the key, and Fig. 5 is a plan view of the improvement arranged as a core arbor, to be used in cores for casting pipes having a plurality of branch pipes.

The main core arbor A is provided with an integral socket B for receiving a key C integrally projecting from the inner end of the branch core arbor D, to allow of joining the said branch core arbor D to the main core arbor A at an angle thereto, the angle varying according to the particular pipe specials to be manufactured, that is, whether the pipe is to be a Y-pipe, a T-pipe or the like. In the manufacture of a cross pipe, use is made of a main arbor A' (see Fig. 5), provided on opposite sides with two integral sockets B', B'', for receiving the keys of branch core arbors D', D''. As the sockets and keys are

alike in construction, it suffices to describe but one in detail. Each socket B is provided with a key hole B³ (see Fig. 3) for the passage of the correspondingly-shaped bit C' of the key C, and the sides B⁴ of the key hole B³ are beveled or formed with cam surfaces at the inner ends, so that the bit C' in passing on the said cam surfaces causes the key C and consequently the branch arbor D, D' or D'' to be drawn inward, to securely interlock the branch core arbor with the main core arbor A. The face of the socket B is engaged by a flange C² formed on the key C, so that when the key C engages the socket and the branch core arbor D, D' or D'' is given a quarter turn and drawn inward by the cam surfaces of the sides B⁴, then the said flange C² is firmly drawn in contact with the face of the socket B, to securely hold the branch core arbor D, D' or D'' in position on the main core arbor A or A'.

From the foregoing it will be seen that in order to connect a branch core arbor with the main core arbor, it is only necessary for the arbor operator to engage the key C with the socket B and then give a quarter turn to the branch core arbor, to securely interlock the core arbor and to bring the cores in proper relation to each other. When it is desired to break up a core, it is only necessary to give a quarter back turn to the branch core arbor D, D' or D'', to unlock the key C in the socket B and to allow of withdrawing the key of the branch core arbor D from the said socket.

Having thus described our invention, we claim as new and desire to secure by Letters Patent:

1. A core arbor, comprising a main core arbor, and a branch core arbor, one of the arbors having a socket and the other having an integral key for engagement with the said socket and adapted to be turned therein, the key and socket having cam surfaces for engagement one by the other, whereby when the key engages the socket and the core arbor carrying the key is turned, the key is drawn inward in the socket.

2. A core arbor, comprising a main core arbor having a circular socket provided with an end wall having a key hole opening therein, the inner surface of the end wall at opposite sides of the key hole being beveled, and a branch core arbor having an integral key projecting from its inner end and adapted to

pass into the socket, the bit of the key corresponding to the shape of the key hole, and adapted to engage the beveled surface at the end of the socket to draw the branch core arbor inward when the latter is turned, the key having a circular flange spaced from the bit for engagement with the outer face of the end wall of the socket, when the core arbors are interlocked.

10 3. In core arbors for the manufacture of pipes having integral branches, the combination with a solid main core arbor having an integral socket located between its ends and arranged at an angle thereto, the outer end 15 wall of the socket being provided with a key-hole entrance and the inner surface of said

end wall being beveled, and a solid branch core arbor having an integral key projecting from its inner end and adapted to pass into the socket and to be turned therein in engagement with the said beveled surface, the said key having a flange spaced from the key bit and adapted to engage the outer face of the end wall of the socket.

20 In testimony whereof we have signed our names to this specification in the presence of two subscribing witnesses.

IRVING HODGSON LONG.

SAMUEL AUGUSTUS MILLIGAN.
